BAR MOUNTING FIXTURE

Otto E. Steizer, South Bend, Ind.

Application August 16, 1947, Serial No. 768,972

3 Claims. (Cl. 211—123)

1

This invention relates to improvements in bar mounting fixtures, and more particularly to a device including a bar usable for various purposes, such as a towel bar, a handle member, a door pull, a guard bar or rail, or the like.

The primary object of the invention is to provide a device of this character having a pair of strong supporting brackets, a decorative member concealing each bracket, and a bar adapted to be supported by the brackets and detachably interlocked therewith wherein the construction is readily assembled and disassembled without requiring the use of securing means separate from said parts and wherein said parts and bar cooperate to positively lock said decorative portions in stationary operative relation when the device is assembled.

A further object is to provide a device of this character which is simple in construction, strong, easy to assemble, and which uses securing means, all of which are concealed when the device is assembled.

Other objects will be apparent from the following specification.

In the drawing:

Fig. 1 is a side view of the device with parts broken away.

Fig. 2 is a fragmentary face view of the device with parts shown in section.

Fig. 3 is a face view of a modified embodiment of the invention with parts shown in section.

Fig. 4 is a side view of the device illustrated in Fig. 3 with parts thereof shown in section.

Referring to the drawing, and particularly to Figs. 1 and 2 which illustrate one embodiment of the invention, the numeral 10 designates a rigid bracket or anchoring member, here shown as an angle iron, having one leg 12 thereof adapted to bear flat against a supporting surface and to be secured thereto by screws or other securing means 14. The other leg portion 16 of the anchoring member extends substantially perpendicularly from the base part 12 and has an aperture 18 formed therein adjacent its outer end. A second bracket 20 having a base flange 22 secured to a support by a screw 24 has a perpendicularly extending leg 26 in which a screw-threaded aperture 28 is formed in the same relation to the base leg 22 as the aperture 18 bears to the base leg 12 of the bracket 10. An elongated rigid bar 30 is adapted to span the two brackets 10 and 20, being of a diameter to fit snugly in the aperture 18 of the bracket 10 and having its opposite end screw-threaded at 32

2

for threaded engagement with the threaded aperture 28 of the bracket 20.

A pair of similar decorative hollow caps 34 are adapted to fit around and conceal the two anchor brackets 10 and 20. These decorative members may be of any desired contour which is attractive in appearance and are preferably of substantially cup-shaped form. Each of these caps 34 has an inner wall 36 provided with an aperture 38 in which the bar 30 is adapted to have a snug slide fit when said aperture is positioned concentrically with said bar. The caps also are provided with side walls 40 preferably having vertical enlargements at the corner portions adjacent the inner walls 36 and grooved at 42 to fit snugly and slidably upon the leg portions 16 and 26 of the respective brackets 10 and 20. The caps may be formed of metal, plastic, glass or any other suitable material and may be of comparatively weak construction inasmuch as they are not required to sustain any of the stresses applied to the device. The open end of the cap is preferably bounded by an edge lying in a flat plane to bear continuously against the wall or the surface to which the base legs 12 and 22 of the anchoring members 10 and 20 are secured when the aperture 38 thereof registers with the bar 30.

In the use of the device, the bracket 10 is first secured in desired position to the wall, door or other support by the securing screw 12. A cap 34 is then applied thereover by the sliding guide fit of the grooves 42 in its side wall portions with the opposite side margins of the flange 16 of the anchor member 10. When the cap 34 is urged to place with its free edge bearing against the surface on which the bracket base leg 12 is secured, it will completely conceal the bracket 10, and its aperture 38 will register with the aperture 18 of the bracket leg 16. The bar 30 may then be slid through the registering apertures 38 and 18 to the dotted line position shown in Fig. 1. Thereupon the bracket 20 is secured to the supporting surface with its threaded aperture 28 in axial alignment with the aperture 18 of the bracket 10. The cap 34 for the bracket 20 is then applied to operative position. Thereupon the rod is slid lengthwise, that is, to the left from the dotted line position in Fig. 1, passing through the opening 38 of the cap 34 and inwardly for engagement of its screw-threaded end portion 32 with the screw-threaded aperture 28 of the bracket. Rotation of the bar will firmly interlock the same with the bracket 20 and the parts

will thereupon be held in their operative assembled position.

It will be observed that by virtue of this construction, the movement of the cap is entirely and completely prevented. The inward movement of the cap is limited by the brackets to a sliding movement in one direction only, and the subsequent application of the bar to extend at an angle to the direction of sliding movement of the cap positively anchors and locks the decorative cap in place.

The parts may be formed of any suitable material and it will be apparent that the device may be used for any of a number of purposes either as household fixtures or as hardware items. Thus, as mentioned above, the device is well suited as a towel bar, a handle member, a door pull, or a guard bar or rail as for stairways and the like. It will be apparent that the securing members 14 and 24, being positioned within the caps 34, are completely concealed and likewise that the threaded engagement of the bar with the bracket 26 at 32 may be concealed. The sizes of the openings 18 of the bracket 10, and 38 of the cap 34, will preferably be limited to that providing a snug slide fit of the bar therein, thus preventing loose fits and free play, and also serving further to conceal the securing means.

A modified embodiment of the invention is illustrated in Figs. 3 and 4. In this form of the invention, the anchor members constitute cup-shaped rigid members, each having a base 50 and endless side walls 52, here shown as cylindrical in form. The base plate is welded or otherwise secured at one end of the cylindrical member 52 and has a central aperture therein adapted to receive a screw 54 by means of which the anchor members may be secured in place. One of the anchor members is provided with an aperture 56 extending radially through one of the side walls 52 thereof adjacent the outer end of said side wall and in spaced relation to the base 50, as illustrated at the right in Fig. 3. The other anchoring member, as illustrated at the left in Fig. 4, has a similarly positioned radial aperture which is internally screw-threaded. Decorative caps of hollow construction open at one end are adapted to fit snugly around the side walls 52 of the anchor members. As best illustrated in Fig. 4, each of these decorative caps comprises an endless wall 58 and an outer end plate 60. While both the anchor member and the end caps have here been shown as of cylindrical form, it will be understood that the forms utilized may be of other configurations and that the contour of the cap need not be the same as the contour of the anchor member, provided that the contours of these parts shall be such that the cap has a snug guided slide fit upon the walls 52 of the anchor member. Each of the caps 58 has an aperture 62 therein preferably of substantially the same size as the aperture 56 in the anchor member adapted to fit snugly around a bar 64 of a length greater than the minimum spacing between the anchor members. One end 66 of the rod 64 is screw-threaded for engagement with the tapped aperture anchor member 52, as shown in Fig. 4. This form of the invention has all of the advantages of the preferred embodiment of the invention above mentioned and differs primarily in that it utilizes parts of different structural shapes than those shown in Figs. 1

and 2. This form of the device is assembled in the same manner described above with reference to the Fig. 1 form of the device.

While two embodiments of the invention have been illustrated and described herein, it will be understood that changes in the construction of the device may be made within the scope of the appended claims without departing from the spirit of the invention.

10 I claim:

1. A device of the character described, comprising a pair of brackets adapted to be mounted on a support in spaced relation and each including a guide portion having a bar-receiving aperture, a bar fitting in said apertures at its opposite ends, and a pair of decorative caps each having a guided slide fit on a bracket and a bar-receiving aperture registering with the bracket aperture, said guide portion including a rigid plate portion disposed substantially perpendicular to said bar and said cap having interior grooves having a snug sliding fit on the opposite margins of said plate portion.

2. A device of the character described, comprising a pair of rigid anchor members each having a base adapted to be secured to a support and a guide projecting substantially perpendicular from said base and provided with an aperture, a rigid rod, said anchor members being positioned with said apertures aligned and spaced a distance less than the length of said rod, and a pair of decorative hollow caps each having a rod-receiving aperture, said caps being slideable on said guides and normally held in operative position on said guides by the bars passing through the apertures thereof, the spacing between the apertured wall portion of one cap and the inner face of the wall portion of the other cap opposite to its aperture being greater than the length of said rod.

3. A device of the character described, comprising a pair of rigid anchor members each having a base adapted to be secured to a support and a guide projecting substantially perpendicular from said base and provided with an aperture, a rigid rod, said anchor members being positioned with said apertures aligned and spaced a distance less than the length of said rod, and a pair of decorative hollow caps each having a rod-receiving aperture, said caps being slideable on said guides and normally held in operative position on said guides by the bars passing through the apertures thereof, the spacing between the apertured wall portion of one cap and the inner face of the wall portion of the other cap opposite to its aperture being greater than the length of said rod, and means on one end of said rod and the cooperating anchor member for detachably interlocking said rod and member.
